SPARK PLUG

Harley W. Sechrist, Newark, Ohio

Application November 30, 1948, Serial No. 62,651

2 Claims. (Cl. 123—169)

1

This invention relates to improvements in spark plugs.

The object of the invention is to provide a novel type of spark plug.

Another object of the invention is to provide a spark plug having an electrode which is highly resistant to deterioration due to electrical influences with high temperatures.

A further object of the invention is to provide a spark plug which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a top plan view of the spark plug, according to the present invention;

Figure 2 is an enlarged sectional view taken on the line 2—2 of Figure 1;

Figure 3 is a sectional view taken on the line 3—3 of Figure 2.

Referring in detail to the drawings, the spark plug comprises an insulator 10 fabricated of porcelain. The insulator is provided with a bore 11 extending from one of the ends thereof, and extending from the other end of the insulator 10 is an enlarged recess 12 which communicates with the bore 11. Positioned within the bore 11 is a tubular jacket 13 fabricated of tungsten steel, and a disk-shaped end of the jacket 13 abuts an end of a tubular cooling chamber 14 which is arranged in the recess 12.

Extending through the jacket 13 and through the cooling chamber 14 is an elongated center electrode 15 fabricated of copper. The electrode 15 is fabricated of copper which has been heat treated, as in a furnace, and the electrode 15 is welded to the steel jacket 13 so that there will be no loss of compression therebetween. The cooling chamber 14 is provided with an enlarged socket 16 which surrounds a portion of the electrode 15 to provide a cooling means for the latter. The cooling chamber 14 is provided with a plurality of radially-disposed apertures or openings 17 for the passage therethrough of air to and from the interior of the cooling chamber. The upper end of the cooling chamber 14 is threaded exteriorly, as at 18, and threaded thereon is a suitable terminal connector 19.

The insulation 10 is mounted in the usual shell, indicated at 20, and the shell is fabricated of metal screw stock. A bushing 21 surrounds the insulator 10 and is in threaded engagement with

5 a portion of the shell 20 for maintaining the parts in assembled relation. A pair of gaskets 22 and 23 fabricated of copper are interposed between the shell 20 and the insulator 10 for providing a fluid-tight connection.

The lower portion of the shell 20 is threaded exteriorly, as at 24, for engagement with the engine housing and dependently carried by the bottom of the shell 20 is a sparking point 25 which is fabricated of tungsten alloy.

From the foregoing, it will be apparent that a spark plug has been provided which includes a single copper electrode 15 that extends completely therethrough. This electrode provides an excellent conductor for electrical energy. The steel jacket serves to protect the electrode 15 against deterioration or corrosion caused by heat and electrical influences under high temperatures.

20 As many embodiments may be made of this inventive concept, and as many modifications may be made in the embodiment hereinbefore shown and described, it is to be understood that all matter herein is to be interpreted merely as 15 illustrative and not in a limiting sense.

I claim:

1. In a spark plug, an insulator fabricated of porcelain provided with a bore extending therethrough for a portion of its length, there being a recess extending from the other end of said insulator and communicating with said bore, a tubular jacket fabricated of tungsten steel positioned within said bore, a disk shaped end on said jacket within said recess; a cooling chamber seated on said disk shaped end in said recess, there being a plurality of radially-disposed apertures in said chamber for the passage therethrough of air, an electrode fabricated of copper extending through said cooling chamber and jacket, a shell arranged in embracing relation with respect to the lower portion of said insulator and operatively connected to the latter, and a spark plug point dependently carried by said shell, said spark plug point being fabricated of a tungsten alloy, said spark plug point having an L-shape, the inner surface of said cooling chamber being spaced from the outer surface of said electrode, the lower portion of said insulator extending below said shell, and the jacket extending below said insulator for a distance equal to the exposed end of the electrode.

2. In a spark plug, an insulator fabricated of porcelain and provided with a bore extending therethrough for a portion of its length, there being a recess extending through a portion of

said insulator and communicating with said bore, said recess being of a greater diameter than said bore, a tubular jacket fabricated of tungsten steel positioned within said bore and having a disk like portion projecting beyond the latter, a cooling chamber projecting longitudinally through said recess and having one end abutting the disk like portion of said jacket, said cooling chamber having a portion projecting beyond said insulator, said projecting portion of said cooling chamber being provided with a plurality of radially disposed apertures for the passage therethrough of air and external threads above said apertures to receive a terminal connection, an electrode fabricated of copper extending through said cooling chamber and jacket and the projected portion of the cooling chamber and rigidly fixed to said jacket, a shell arranged in embracing relation with respect to the lower portion of said insulator and operatively connected to the latter, and a spark plug point dependently carried by said shell, said spark plug point being fabricated of a tungsten alloy, said spark plug point having an L-shape, the inner surface of

said cooling chamber being spaced from the outer surface of said electrode, the lower portion of said insulator extending below said shell, and the jacket extending below said insulator for a distance equal to the exposed end of the electrode.
